UNITED STATES PATENT OFFICE.

FRANK G. CURTIS, OF ST. PAUL, MINNESOTA, ASSIGNOR TO LEOPOLD A. GUITERMAN,
OF ST. PAUL, MINNESOTA.

NECK-PROTECTOR FOR COATS.

1,016,214.

Specification of Letters Patent.

Patented Jan. 30, 1912.

Application filed February 14, 1910. Serial No. 548,691.

To all whom it may concern:

Be it known that I, FRANK G. CURTIS, a citizen of the United States, residing at St. Paul, in the county of Ramsey and State of Minnesota, have invented certain new and useful Improvements in Neck-Protectors for Coats, of which the following is a specification.

My invention relates to improvements in neck protectors for coats, its object being to provide improved means for protecting the neck of the wearer from the weather.

The invention is applicable to overcoats, waist-coats or vests, jackets, and other coats of every sort, whether made with or without a collar, but is particularly useful to form a neck protector for overcoats to be secured upon the coat inside of the regular storm collar so as to seal the open space between the coat collar and the wearer's neck; and also to serve as a muffler to fill the open space in front between the lapels or meeting portions of the coat collar. To this end I have designed a neck protector so knitted and constructed that its inner edge can be readily secured to the coat, while its outer or exposed edge will fit snugly and elastically to the neck without the use of any rubber or other foreign elastic instrumentality.

More particularly the invention consists in the features of construction, combination and arrangement of parts hereinafter described and claimed.

In the accompanying drawings forming part of this specification, Figure 1 is a perspective view of the neck portion of an overcoat fitted with the improved protector, the coat and protector being shown closed in front; Fig. 2 is an inside view of a fragment of the neck portion of a coat with both storm collar and protector turned up, showing the knitted work of the protector; Fig. 3 is a perspective view of the protector alone when folded and ready for attachment to the coat, a part only of the knitted work being shown; and Fig. 4 is a plan view of a blank or strip A of the knitted fabric of which the protector is made.

In the construction of this strip the tension of the machine is adjusted from time to time so as to form a fabric having symmetrical zones of progressively tighter knitting up to a certain point and then progressively looser knitting to another point. Each zone may comprise a single line of

knitting, or, as shown in the drawings, a plurality of lines of knitting of equal tension, but the zones as a whole are of progressively tighter and then looser tension, as above stated. For instance at the top of 60 the strip is a zone 2 of loose knitting, which merges into a zone 3 of tighter tension, and zone 3 in turn merges into a zone 4 of still tighter tension. Zone 4 then merges into a zone 5 of looser tension corresponding to 65 zone 3; and zone 5 merges into a zone 6 of still looser tension corresponding to zone 2. Thus is formed a strip having symmetrical loose tensioned end zones 2 and 6 of equal width, symmetrical intermediate zones 3 70 and 5 of somewhat tighter tension and of equal width, and a central or middle zone 4 wherein the tension is greatest.

After the strip has been knitted as described, it is cut along the lines 7 and 8 at 75 the ends of the loose zones 2 and 6. These lines of cutting are curved inwardly so that the end portions 9 and 10 will extend down to form a filler for the open space between the lapels of the coat, when the protector is 80 used with a coat having a turned or folded collar. After the fabric has been cut to the requisite length, it is folded over upon itself along its transverse medial line 11 so as to bring the edges 7 and 8 together. The line 85 of fold will thus be directly across the middle of the zone 4 of greatest tension, and the zones 2 and 3 will coincide with the corresponding zones 5 and 6 on the other side of the line of fold, as best shown in Fig. 3. 90 The folded portions are then secured together by stitching 12 or otherwise, as may be most convenient, and the meeting ends are provided with coöperating fastening members 13 and 14 whereby the two ends 95 may be secured together in the position shown in Fig. 1. The neck-protector thus formed will assume the shape of a hollow truncated cone, and may be stitched or otherwise secured along its lower-unfolded edge 100 to the neck opening of the coat. In Figs. 1 and 2 it is shown stitched by stitching 15 into the seam between the storm collar B and the body portion C of the coat, with its folded edge uppermost and free. If desired, 105 however, the protector, instead of being sewn or otherwise permanently secured to the coat body, may be made with fastening members 16 arranged along its lower edge in position to engage either the coat itself, or coöperat- 110

ing fastening members (not shown) arranged thereon, whereby it can be detachably secured to the coat, if it is preferred to have the protector detachable.

5 It will be observed that, by securing the neck protector to the coat along its lower edge only, it will stand free from the collar, so that it can be turned up or down irrespective of the position of the collar; and by making the protector of knitted fabric folded over and doubled upon itself with a tighter tension along the neck-engaging line-of-fold 11 than at its lower edge where it is secured to the coat body, the protector will be made to 10 fit snugly and elastically about the neck of the wearer, the freedom of the protector from the collar allowing its elasticity to have full play. This result is most perfectly and effectually accomplished by knitting the fabric in zones of progressively tighter tension from the edge where it is secured to the coat 15 toward the medial line of fold 11.

It will also be observed that by making the protector wider at the ends than at the 20 middle, the protector will be deeper at the front than at the back, and the downwardly projecting portions 9 and 10 will extend down to about the point where the two por-

tions of the outer collar or lapels of the coat meet or overlap and thus form a complete 30 closure for the front portion of the neck and the upper portion of the chest of the wearer.

I claim as my invention:

The combination with a coat, of a neck protector comprising a strip of knitted fabric having transverse zones of different tension, the tension of said zones being progressively greater from the edges of the strip to the middle portion thereof, said strip being folded on the medial line of the zone of greatest tension and having zones of equal tension disposed symmetrically on either side of the line of fold, whereby to exert a maximum of uniform tension at the portion immediately contiguous to the neck, said strip being secured to the neck portion of the coat along its unfolded edges, and coöperating fastening means upon the meeting ends of the protector.

In testimony whereof I affix my signature 50 in presence of two witnesses.

FRANK G. CURTIS.
